UNITED STATES PATENT OFFICE.

JOSEPH WHITE, OF BOUNDBROOK, NEW JERSEY, ASSIGNOR TO THE
ALUMINUM PRESS, OF NEW YORK, N. Y., A CORPORATION OF NEW
YORK.

CYLINDER ADJUSTMENT FOR PRINTING-MACHINES.

No. 833,275.

Specification of Letters Patent.

Patented Oct. 16, 1906.

Application filed October 8, 1905. Serial No. 281,707.

To all whom it may concern:

Be it known that I, JOSEPH WHITE, residing at Boundbrook, Somerset county, State of New Jersey, have invented certain new and useful Improvements Relating to Cylinder Adjustments for Printing-Machines, where fine adjustment both for the purpose of getting the proper printing-pressure and for the purpose of registering the designs 10 with relation to each other, of which the following is a specification.

In a multicolor-press such as is illustrated in the drawings it is desirable that these adjustments can be readily and positively 15 made as well when the machine is in printing operation as when it is standing still, and the improvements herein shown are devised for these purposes.

Although the improvements may be readily 20 applied to printing-machines of various descriptions, it is more particularly adapted to a machine of the type illustrated, which is a multicolor rotary lithographic press.

Referring to the drawings, Figure 1 is an 25 elevation of a two-color planograph-machine, such parts being shown as are necessary to illustrate the improvements embodied in this invention. Fig. 2 is an enlarged view of one 30 of the cylinder-bearings. Fig. 3 is a sectional view taken on the line 3 of Fig. 2.

Referring to Fig. 1, 1 represents the impression-cylinder of the machine. 2 is the ordinary gripper, operated in any usual or desired manner to take the sheets from the 35 feed-board 3, and in the printing operation said sheet is carried around the impression-cylinder in the direction of the arrow, receiving the first impression from the design-face 4, which is a planograph form, preferably of 40 aluminium, which has been clamped to the form-cylinder 5, and on its continued forward movement the sheet receives its second color from the planographic form 6, which is clamped to the form-cylinder 7, and continuing 45 in its movement the sheet is delivered in the usual manner by mechanism. (Not shown.)

The cylinders 1, 5, and 7 are geared together by gears fastened to their respective 50 shafts, said gears being equal in pitch diameter to the printing-surfaces.

It is necessary that the two designs im-

pressed upon the sheets in the printing operation must be in exact register with each other and both laterally and circumferentially, and in order to facilitate lateral adjustment while the press is running or stationary I have provided the following methods, which accomplish this purpose positively: The usual form of mounting a printing-cylinder is to have the cylinder mounted so as to be guided laterally between fixed shoulders in supporting-frames or journal-boxes, and in this case when lateral adjustment of forms are required it is necessary to stop the machine and loosen the forms from their fastenings, adjust the form on the cylinder, and reclamp the same. In the method shown the cylinder is so mounted that it can be adjusted laterally in its bearing, carrying the form with it, and thereby accomplishing the desired adjustment much more readily. The manner of accomplishing this may be varied widely.

Referring to Figs. 2 and 3, 8 is the journal-box, which is mounted in the frame 9, said box containing the eccentric sleeve 10, (whose function will be hereinafter described,) in which sleeve the journal 11 of the cylinder finds its bearing. This journal 11 is 80 provided with a projection 12, fastened to which is a collar 13. The inner face of this collar 13 and projection 12, it can be seen, forms an annular groove. In this annular groove is placed the sleeve 14, which is laterally adjustable to the cylinder-box and forms the adjustable guide which holds the cylinder in its proper lateral position. The manner in which this guide may be adjusted may be varied widely; but in the construction shown, which is the preferred form, the cylinder box or bearing 8 has a part attached to it in a relatively fixed lateral position, preferably in the form of the bracket 15, which is generally circular in form and contains a hollow threaded cylindrical portion 16, which encircles the cylinder end 12, the hole of which being somewhat larger than the cylinder end 12.

Although shown fastened to the cylinder-box and forming a part of it, the bracket 15 or its mechanical equivalent might readily be fastened to the frame instead. Mounted on this part, which is relatively laterally fixed in

relation to the cylinder, is an adjustable part, preferably as the sleeve 14. This sleeve 14 has formed on its inside a threaded portion, which engages the thread on the bracket 15, and therefore is, in effect, a nut engaging the screw on 15, and as the sleeve 14 is held by and works into the annular groove formed at the end of the cylinder it will carry this cylinder laterally in the direction required accordingly as this nut is adjusted inward and outward. The manner in which this sleeve may be adjusted may be varied widely; but it is preferable to operate it in the manner shown by means of a screw or worm, as in this way a very fine adjustment can be readily effected, and at the same time it is self-locking. Upon the outer portion of the sleeve 14 is formed teeth, making it, in effect, a worm-gear in which meshes the adjusting-worm 17, said worm being mounted on a spindle 18, which finds its bearing in the puppets 19, fastened to the bracket 15, said spindle having pin-holes for the purpose of moving same. When this worm is moved in one direction or the other, it will, through the parts shown, carry the cylinder laterally in the direction required.

In a machine of the type shown it is necessary for various purposes—such, for instance, as when a sheet is missed or on inking up on starting the job—to bring the form-cylinders to and from the impression-surface at the will of the operator, and in the construction shown this is accomplished by eccentrically mounting the form-cylinders in cylindrical bearings and rocking said bearings, so as to move the center of the cylinder to and from the impression-cylinder. The manner in which this moving may be accomplished does not form part of this application; but a preferred form is shown in my companion application, Serial No. 281,708.

The cylindrical journal-box 8, mounted in the frame 9, is held laterally in position by means of the eyepiece 20, which is connected to the tripping mechanism and the flange 21 on the other side.

It can be seen that the mechanism for lateral adjustment being contained on the cylinder-box is not in any wise affected by the movement of the eccentric box and can just as readily be adjusted, no matter what position the eccentric box may be placed in.

As has been previously mentioned, the journal-box 8 is provided with the sleeve 10. This sleeve is supplied for the purpose of effecting the pressure-regulation required, said sleeve being eccentrically mounted in the journal-box 8, and therefore when it is rotated in said box it tends to vary the printing-pressure when said pressure is applied. The manner in which this sleeve is adjusted is, as can be seen, similar in design to the parts accomplishing the lateral adjustment. The flange 22, formed on the outside eccentric

sleeve 10, has teeth which serve as a worm-gear for the pressure-adjusting worm 23, which is mounted on the spindle 24, which finds its bearing in the lugs 25 and the cylinder-box 8, and as said worm-gear is moved in one direction or the other it will increase or relieve the pressure, as required. It can be seen that by this method the adjustment can be effected while the press is running and also regardless of the position in which the eccentric box is placed when tripping or putting the cylinders in impression. It is to be noted that bracket 15, which serves the purpose of holding the lateral adjustment parts, also acts as a guide in which the flange 22 of the pressure-regulating sleeve 10 is guided.

I claim—

1. In a printing-machine having a form-cylinder mounted in a pair of cylinder-boxes, said boxes being movable for the purpose of tripping the cylinder, and parts mounted on a cylinder-box whereby the cylinder may be adjusted laterally; said cylinder-boxes and associated parts arranged so that the form-cylinder may be moved to and from the impression-cylinder without disturbing the lateral adjustment of the form-cylinder.

2. In a printing-machine having a form-cylinder eccentrically mounted in cylindrical cylinder-boxes, said boxes arranged to partially rotate for the purpose of tripping the cylinder, and parts mounted on a cylinder-box whereby the cylinder may be adjusted laterally; said cylinder-boxes and associated parts arranged so that the form-cylinder may be moved to and from the impression-cylinder without disturbing the lateral adjustment of the form-cylinder.

3. In a printing-machine having a form-cylinder eccentrically mounted in cylindrical cylinder-boxes, said boxes arranged to partially rotate for the purpose of tripping the cylinder, and parts mounted on a cylinder-box whereby the cylinder may be adjusted laterally, and means for locking said parts in their lateral adjustment; the cylinder-boxes and associated parts so arranged that the form-cylinder may be moved to and from the impression-cylinder without disturbing the lateral adjustment of the form-cylinder.

4. In a printing-machine, the combination of a cylindrical cylinder-box in which the cylinder is eccentrically mounted, an eccentric journal-sleeve in the cylinder-box, a part laterally fixed on the cylinder-box and a part laterally adjustable on said fixed part, the laterally-adjustable part engaging the cylinder end to locate the cylinder laterally.

5. In a printing-machine, the combination of a cylindrical cylinder-box in which the cylinder is eccentrically mounted, a worm-adjusted eccentric journal-sleeve in the cylinder-box, a part laterally fixed on the cylinder-box, and a part laterally adjustable on

said fixed part by means of a worm, the laterally-adjustable part engaging the cylinder end to locate the cylinder laterally.

6. In a printing-machine, means for adjusting a form-cylinder laterally, comprising in combination a hollow externally-threaded cylindrical part fixed to the cylinder-box; an internally-threaded nut engaging said fixed part, having a flanged portion engaging an annular groove at the form-cylinder end; a

worm engaging said nut for the purpose of adjusting the nut to locate the cylinder laterally.

In witness whereof I have hereunto set my hand in the presence of two subscribing witnesses. 15

JOSEPH WHITE.
